CANISTER FOR DEHUMIDIFYING CRYSTALS OR A SIMILAR ARTICLE

Leonard R. Gaylord, Gates, N.Y., assignor to
International Valide Corp., Rochester, N.Y.

Filed Dec. 16, 1970, Ser. No. 26,527

Term of patent 14 years

Int. Cl. D23—99

U.S. Cl. D23—146

FIG. 2

FIG. 3

FIG. 1 is perspective view of a canister for dehumidifying crystals or a similar article showing my new design; FIG. 2 is a top plan view thereof; and

FIG. 3 is a side elevational view thereof.

The bottom is plain.

I claim:

The ornamental design for a canister for dehumidifying crystals or a similar article, substantially as shown and described.
